TABLE FIXTURE

Henry E. Brunhoff, Wyoming, Ohio, assignor to
The Brunhoff Manufacturing Company, Cincinnati, Ohio, a corporation of Ohio

Application April 24, 1933, Serial No. 667,513

1 Claim. (Cl. 211—74)

This invention relates to a combined smoker's tray and tumbler service rack or fixture for tables, ledges, and the like, formed of sheet metal and adapted to be clasped about and clamped to the 5 corner of a table to serve two sides thereof.

An object of the invention is to provide a fixture of simple and durable structure and for convenient adjustment to a corner of a table for smokers' and refreshment service.

10 Another object of the invention is to provide a corner fixture for a table with a pair of tumbler holders extending from the table for respectively serving adjoining sides thereof.

15 Other objects and further advantages will be more fully apparent from a description of the accompanying drawing, in which:

Figure 1 is a perspective view of the improved smoker's tray and tumbler service rack or fixture shown as applied to a corner of a table, the 20 corner section of the table being shown in dot and dash lines.

Figure 2 is a section on line 2—2, Figure 1.

Figure 3 is a section on line 3—3, Figure 1.

25 Figure 4 is a perspective view of slightly modified form of fixture.

The combined tray and rack is preferably constructed of sheet metal and adapted to be secured to the corner of either a round or square cornered table and is particularly adaptable for card table 30 service, although it can be applied to the arms of chairs or ledges of any sort.

Referring to the drawing, 1 indicates a sheet metal bracket frame for engagement with and securing to the corner of a table or ledge either 35 round or square and consists of a plane base or horizontal tray portion 2 for overlying the top of the table or ledge and provided with a circular embossment or ridge 3 as the confines for an ash tray set therein as shown in dot and dash lines, 40 Figure 1. A portion of the embossment or ridge 3 forms a rounded margin or edge for the inner end of the base, adding to the appearance of the device.

A pair of side walls 4—4 at right angles to 45 each other and to the base, with which they are integral, extend downwardly therefrom to overlie the corner edges of the ledge or table corner to which the fixture is secured. Each side wall 4, at its lower end, is provided with an inturned 50 flange 5 to underlie the table or ledge, and the flanges at the corner of the fixture overlap each other and are spot welded or otherwise secured together for tying the walls against lateral spread or displacement.

55 A bracket plate 6 of approximately triangular outline or configuration is respectively secured to the under side of each flange extending hori-

zontally outwardly therefrom for supporting a dish or circular tray 7 stamped from sheet metal rigidly secured to the plate preferably by spot-welding, and positioned relatively centrally of the side wall for sustaining a glass or tumbler. A 5 guard ring 8 is disposed concentrically above the tumbler holder 7 rigidly fixed to the upper end of the side wall.

A match box or match book holder 9 consisting of a piece of rectangular sheet metal bent into U 10 form, with the opposite ends curved inward and thence downward, provides a pair of outwardly disposed limbs for receiving a match box therebetween, while the body structure of the holder is adapted to be telescopically engaged into a rectangular tube or slide cover of a match box. The match holder is secured to the corner of the fixture and projects slightly therebeyond in line 15 radially with the axis of the ash tray support of the fixture and between the tumbler holders 20 thereof.

The fixture is clamped to a corner of a table or ledge by one or a pair of clamp screws 10 respectively screw-threaded to a bracket plate 6 of a tumbler holder and inturned flange of a side 25 wall, a double thickness of material being sufficient for screw-threading.

The structure of the fixture is very simple, rigid and attractive in design, fitting to either a round or square cornered table, serving two sides of the 30 table. In the modification shown in Figure 4, a single bracket plate 6^a secured to the inturned flanges of the side walls 4—4, provides a common support or base for both tumbler holders and has two circular embossments or ridges 11 respectively in registry with the superposed guard rings 8. The intermediate portion of the support carries a rectangular casing 12 as a receptacle for holding a deck of cards or other articles and the front wall of the casing has a tongue 13 40 of hook form for holding a match book.

Having described my invention, I claim:

A serving fixture as an article of manufacture, comprising, a sheet metal bracket having a horizontal body portion and providing a tray upon 45 its upper surface, extensions at adjoining edges of said body portion respectively bent at an angle thereto, forming depending side walls at an angle to each other, each extension terminating with an inturned flange in parallelism with the body portion and provided with a clamp screw for securing the fixture to a support, and bracket plates respectively extending horizontally outward from said flanges, each providing a tray adjacent its corresponding side wall and below the plane of 55 the body portion.

HENRY E. BRUNHOFF.
